[57] **CLAIM**

The ornamental design for ornamental bolt, as shown and described.

DESCRIPTION

Any undisclosed surface(s) of the article can be reasonably understood to be a mirror image of an opposing or adjacent surface shown. The surface(s) or (portions) of the article not shown in the drawings or described in the specification form(s) no part of the claimed design.

FIG. 1 is a side elevation of an ornamental bolt with light emitting diode with the opposite and adjacent sides being identical in appearance;

FIG. 2 is a bottom plan view of a second embodiment which is shown in FIG. 6;

FIG. 3 is a top view of the embodiments of FIGS. 1 and 6; FIG. 4 is a bottom view of the embodiment of FIG. 1; FIG. 5 is a reduced scale environmental perspective view; and,

FIG. 6 is an elevation of a machine bolt embodiment with a light emitting diode incorporated therein.

The broken line showing of partial automobile and tire is for illustrative purposes only and forms no part of the claimed design.

The cable is shown broken away to indicate indeterminate length.
